TOY STEAM SHOVEL

Oscar F. Strom, Biwabik, Minn.

Application March 18, 1938, Serial No. 196,759

2 Claims. (Cl. 46—40)

This invention appertains to new and useful improvements in toys and more particularly to a toy steam shovel.

The principal object of the present invention is to provide a toy in the nature of a steam shovel or like digging apparatus which can be manipulated in a manner simulating the control of an actual steam shovel.

Another important object of the invention is to provide a construction of the character described which will be durable, positive acting and not susceptible to the ready development of defects.

These and various other important objects and advantages of the invention will become apparent to the reader of the specification.

In the drawings:

Figure 1 represents a side elevational view of the apparatus.

Figure 2 represents a top plan view.

Figure 3 is a fragmentary horizontal sectional view.

Figure 4 is a fragmentary vertical sectional view through the rear portion of the apparatus.

Figure 5 is a fragmentary vertical sectional view through the entire apparatus.

Figure 6 is a rear elevational view of the scoop.

Referring to the drawings wherein like numerals designate like parts, it can be seen that numeral 5 represents the base, preferably constructed of sheet metal from the side portions of which vertically extend the risers 6—6 for supporting the horizontal shaft 7 on which are rockable the levers 8, 9 and 10.

Extending rearwardly from the base 5 are the arms 11—11 which are bridged by the shaft 12 on which are the pulleys 13, 14 and 15 over which are trained the cables or cords 16, 17 and 18, respectively. These cables are trained and guided through wire guides 19 carried by the shaft 12.

Numerical 20 denotes the derrick truck having the wheels 21 on the axles 22 and these axles 22 are anchored in place on the platform 5 by suitable means 23.

Numerical 24 represents the body structure of the derrick from which depends the tube 25 and this tube extends through an opening in the truck 20. The lower end of the tube 25 is flanged outwardly as at 26 for affording a swivelled connection of the tube 25 with respect to the truck 20.

Numerical 27 extend downwardly from the truck 20 and support the rollers 28—29 over which the cables 17—18 extend.

These cables 17—18 extend over the pulleys 14—15 and connect to the lower end of the levers 9—10. One end of the cable 17 connects to the

upper portion of the shovel shank 36 and extends downwardly under the pulley 32 and then backwardly to pass over the double pulley 31 and downwardly through the opening 30 and tube 25 and rearwardly to have the lever 9 connected thereto and then over the pulley 14 to extend forwardly and upwardly through the tube 25 and to pass through opening 30 and over double pulley 31 and over the roller 32 and extend downwardly to connect to the lower portion of the shovel 10 shank 36 by the anchor 17a.

The cable 18 extends over the pulley 33 on the floor of the body 24 and extends upwardly over the large pulley 39 at the upper end of the beam 40 and downwardly to connect to the ball 41 which attaches as at 42 to the shovel 37 at the forward portion thereof.

The cable 16 extends horizontally under the body 24 and around the large pulley 43. This cable 16 is endless and by actuating the lever 8 the pulley 43 can be rotated so as to swing the entire body 24.

By actuating the lever 9, the shank 36 of the shovel 37 can be lifted or lowered with respect to the beam 40 and by actuating the cable 18, the shovel 37 can be lifted or lowered with the pin 33 acting as the fulcrum.

Obviously by simultaneously manipulating the lever 8, which constitutes a body or cab rotating lever, and the lever 9, which constitutes the shank 36 elevating and lowering lever, said cab 24 may be rotated and the shank 36 raised, or lowered simultaneously. Also by simultaneously manipulating said lever 8 and the lever 10, which constitutes the shank swinging lever, the body or cab 24 may be rotated and the shank 36 swung simultaneously. Also by simultaneously manipulating the levers 9 and 10 the shank 36 may be simultaneously raised, or lowered, and swung as desired.

The shovel 37 is of the open back type adapted to be closed at its rear by a flap-like gate 47 provided at its top edge and adjacent opposite sides thereof with a pair of upwardly bowed hinge leaves 44 by means of which and pins 44' said gate is pivoted to the sides of said shovel for movement under the influence of gravity to opened and closed positions in different angular positions of the shovel shank 36 and the shovel 37.

The gate 47 is adapted to be releasably latched in closed position by means of a latching frame 43 slidably mounted in guides 43' on the rear side and lower end of the shovel shank 36 for gravitational movement in one direction to latching position and for operation in the opposite direction into unlatching position. Under movement 45

of said frame 43 in a latching direction, a curved resilient finger 45 thereon rides over the lower edge of a slot 46 in the upper edge of the gate 47 and thereby cams said gate closed. A pull line 5 42' is provided for operating the latching frame in an unlatching direction, said line being connected to said frame, as at 44a, and anchored to the top of the body structure 24, as at 42b.

Obviously, if the frame 43 is moved to unlatching position, and the shovel shank 36 swung out of vertical, the gate 47 will swing open to permit the shovel 37 to dump the contents thereof. As will be understood the frame 43 may be moved manually to latching position at any time if 15 desired.

While the foregoing specification sets forth the invention in specific terms, it is to be understood that numerous changes in the shape, size and materials may be resorted to without departing from 20 the spirit and scope of the invention as claimed hereinafter.

Having described the invention, what is claimed as new is:

1. In a toy power shovel, an elongated base, a 25 cab rotatably mounted on one end of said base, a boom extending upwardly from said cab, a shovel shank pivotally and slidably mounted on said boom for swinging and endwise operation thereon, and remote control means for simultaneously rotating said cab and operating said shank comprising a plurality of pulleys rotatably mounted on said base adjacent the opposite end of the latter, cable connections between said pulleys and said cab and shank, respectively, and hand levers

operatively connected to said cables adjacent to said pulleys, the cable connection to said shank extending from its related pulley beneath said cab and having a portion extended upwardly through the latter, and the mounting for said cab being constructed and arranged for rotation of said cab about said portion, whereby fouling of said cable connection by said cab under rotation thereof is obviated.

2. In a toy shovel, an elongated base, a cab, 10 means to mount said cab at one end of the base for rotation thereon comprising a truck, a hollow sleeve depending from the floor of the cab and journaled at its lower end in said truck, the ends of the sleeve being open, a boom extending upwardly from the floor of the cab out of the same, a shovel shank endwise movable in opposite directions on said boom, remote control means for rotating said cab, and remote control means for moving said shank comprising an idler pulley 15 rotatably mounted at the other end of said base, a pair of lower and upper pulleys mounted on said truck and the top of said cab, respectively, a cable trained around said idler pulley and under and over said lower and upper pulleys, respectively, 20 said cable extending through said sleeve and having its ends operatively connected to said shank to move the same in opposite directions under operation of said cable in opposite directions, and a lever pivotally mounted at said other end of the 25 base and operatively connected to said cable to move the same.

OSCAR F. STROM.
